Primary Examiner — Troy Chambers*Assistant Examiner* — Bridget A Cochran(57) **ABSTRACT**

A biometric firearms safety system includes a firearm that has a grip and an action. A fingerprint unit is coupled to the firearm. The fingerprint unit is positioned on the grip to read fingerprints from a user. The fingerprint unit stores fingerprints from an authorized user. A locking unit is coupled to the firearm. The locking unit engages the action such that the locking unit inhibits the action from being manipulated. Thus, the locking unit inhibits the firearm from being loaded and fired. The locking unit is electrically coupled to the fingerprint unit. The locking unit disengages from the action when the user's fingerprints match the authorized user's fingerprints. Thus, the locking unit facilitates the user to load and fire the firearm.

FIG. 3

FIG. 2

FIG. 4

FIG. 5

BIOMETRIC FIREARMS SAFETY SYSTEM

BACKGROUND OF THE DISCLOSURE

Field of the Disclosure

The disclosure relates to safety devices and more particularly pertains to a new safety device for inhibiting an unauthorized user from loading and firing a firearm.

SUMMARY OF THE DISCLOSURE

An embodiment of the disclosure meets the needs presented above by generally comprising a firearm that has a grip and an action. A fingerprint unit is coupled to the firearm. The fingerprint unit is positioned on the grip to read fingerprints from a user. The fingerprint unit stores fingerprints from an authorized user. A locking unit is coupled to the firearm. The locking unit engages the action such that the locking unit inhibits the action from being manipulated. Thus, the locking unit inhibits the firearm from being loaded and fired. The locking unit is electrically coupled to the fingerprint unit. The locking unit disengages from the action when the user's fingerprints match the authorized user's fingerprints. Thus, the locking unit facilitates the user to load and fire the firearm.

There has thus been outlined, rather broadly, the more important features of the disclosure in order that the detailed description thereof that follows may be better understood, and in order that the present contribution to the art may be better appreciated. There are additional features of the disclosure that will be described hereinafter and which will form the subject matter of the claims appended hereto.

The objects of the disclosure, along with the various features of novelty which characterize the disclosure, are pointed out with particularity in the claims annexed to and forming a part of this disclosure.

BRIEF DESCRIPTION OF THE DRAWINGS

The disclosure will be better understood and objects other than those set forth above will become apparent when consideration is given to the following detailed description thereof. Such description makes reference to the annexed drawings wherein:

FIG. 1 is a perspective view of a biometric firearms safety system according to an embodiment of the disclosure.

FIG. 2 is a front view of an embodiment of the disclosure.

FIG. 3 is a left side view of an embodiment of the disclosure.

FIG. 4 is a perspective view of an alternative embodiment of the disclosure.

FIG. 5 is a schematic view of an embodiment of the disclosure.

DESCRIPTION OF THE PREFERRED EMBODIMENT

With reference now to the drawings, and in particular to FIGS. 1 through 5 thereof, a new safety device embodying the principles and concepts of an embodiment of the disclosure and generally designated by the reference numeral 10 will be described.

As best illustrated in FIGS. 1 through 5, the biometric firearms safety system 10 generally comprises a firearm 12 that has a grip 14 and an action 16. The firearm 12 may comprise a handgun or the like. The grip 14 may have a first

lateral side 18. A fingerprint unit 20 is coupled to the firearm 12. The fingerprint unit 20 is positioned on the grip 14 to read fingerprints from a user.

The fingerprint unit 20 comprises a processor 22 that is coupled to the firearm 12. An electronic memory 24 is coupled to the firearm 12. The electronic memory 24 is electrically coupled to the processor 22. The electronic memory 24 stores fingerprints of an authorized user. The processor 22 may comprise an electronic processor or the like. The electronic memory 24 may comprise RAM memory or the like.

A plurality of sensors 26 is provided and each of the sensors 26 is coupled to the grip 14. The sensors 26 are spaced apart from each other and distributed along the grip 14. Additionally, each of the sensors 26 may be positioned on the first lateral side 18 of the grip 14. Thus, each of the sensors 26 may read a fingerprint from an associated one of a user's fingers when the user grips the grip 14. Each of the sensors 26 may comprise an electronic fingerprint reader or the like. In an alternative embodiment 25 as shown in figured 4, a pair of sensors 27 may be provided.

Each of the sensors 26 is electrically coupled to the processor 22. The processor 22 generates an unlock sequence when the sensors 26 read fingerprints that matches the authorized user's fingerprints stored in the electronic memory 24. The processor 22 generates a record sequence when the sensors 26 read fingerprints that do not match the authorized user's fingerprints. Thus, the electronic memory 24 stores the fingerprints that do not match the authorized user's fingerprints.

A power supply 28 is provided. The power supply 28 is coupled to the firearm 12. The power supply 28 is electrically coupled to the processor 22. The power supply 28 comprises at least one battery 30.

A locking unit 32 is coupled to the firearm 12. The locking unit 32 engages the action 16 such that the locking unit 32 inhibits the action 16 from being manipulated. Thus, the locking unit 32 inhibits the firearm 12 from being fired. The locking unit 32 is electrically coupled to the fingerprint unit 20. The locking unit 32 disengages from the action 16 when user's fingerprints match the authorized user's fingerprints. Thus, the locking unit 32 facilitates the user to fire the firearm 12. The action 14 may include a trigger 34 and a slide 36.

The locking unit 32 comprises a lock 38 that is coupled to the firearm 12. The lock 38 is biased into a locking position. Thus, the lock 38 mechanically engages the action 14 to inhibit the action 14 from being manipulated. The lock 38 may inhibit the trigger 34 from being pulled. Thus, the firearm 12 is inhibited from being fired. Additionally, the lock 38 may inhibit the slide 36 from being manipulated. Thus, the firearm 12 is inhibited from being loaded.

The lock 38 is electrically coupled to the processor 22. The lock 38 is actuated into an unlocked position when the processor 22 generates the unlock sequence. Thus, the lock 38 mechanically disengages the action 14 to facilitate the action 14 to be manipulated. The lock 38 may comprise an electrically actuated solenoid or the like.

A button 40 is coupled to the lock 38 and the button 40 may be manipulated. The button 40 urges the lock 38 into the locking position when the processor 22 generates the unlock sequence. Thus, the lock 38 inhibits the action 14 from being manipulated. The button 40 may comprise a gun safety or the like.

In use, the authorized user's fingerprints are uploaded into the electronic memory 24. Each of the sensors 26 reads the user's fingerprints when the user grips the grip 14. The

processor 22 generates the unlock sequence when the user's fingerprints match the authorized user's fingerprints. Thus, the firearm 12 may be loaded and fired.

The processor 22 does not generate the unlock sequence when the user's fingerprints do not match the authorized user's fingerprints. Thus, the firearm 12 may not be loaded and fired. The processor 22 generates the record sequence when the user's fingerprints do not match the authorized user's fingerprints. The user's fingerprints are stored in the electronic memory 24. Thus, the user's fingerprints may be collected for as evidence for legal purposes.

With respect to the above description then, it is to be realized that the optimum dimensional relationships for the parts of an embodiment enabled by the disclosure, to include variations in size, materials, shape, form, function and manner of operation, assembly and use, are deemed readily apparent and obvious to one skilled in the art, and all equivalent relationships to those illustrated in the drawings and described in the specification are intended to be encompassed by an embodiment of the disclosure.

Therefore, the foregoing is considered as illustrative only of the principles of the disclosure. Further, since numerous modifications and changes will readily occur to those skilled in the art, it is not desired to limit the disclosure to the exact construction and operation shown and described, and accordingly, all suitable modifications and equivalents may be resorted to, falling within the scope of the disclosure. In this patent document, the word "comprising" is used in its non-limiting sense to mean that items following the word are included, but items not specifically mentioned are not excluded. A reference to an element by the indefinite article "a" does not exclude the possibility that more than one of the element is present, unless the context clearly requires that there be only one of the elements.

I claim:

1. A biometric firearms safety system comprising:
a firearm having a grip and an action;
a fingerprint unit being coupled to said firearm, said fingerprint unit being positioned on said grip wherein said fingerprint unit is configured to read fingerprints from a user, said fingerprint unit storing fingerprints from a previously authorized user, wherein said fingerprint unit comprises
a processor being coupled to said firearm, and
an electronic memory being coupled to said firearm,
said electronic memory being electrically coupled to said processor, said electronic memory storing fingerprints of the previously authorized user;
a locking unit being coupled to said firearm, said locking unit engaging said action such that said locking unit inhibits said action from being manipulated wherein said locking unit is configured to inhibit said firearm from being loaded and fired, said locking unit being electrically coupled to said fingerprint unit, said locking unit disengaging from said action when fingerprints of a current user match the fingerprints of the previously authorized user wherein said locking unit is configured to facilitate the current user to load and fire said firearm; and
said fingerprint unit further including a plurality of sensors, each of said sensors being coupled to said grip wherein each of said sensors is configured to read the fingerprint from a respective finger of the current user when the current user grips said grip, each of said sensors being electrically coupled to said processor, said processor generating an unlock sequence when said sensors read fingerprints of the current user match

the fingerprints of the previously authorized user stored in said electronic memory, said processor generating a record sequence when said sensors read fingerprints that do not match the authorized user's fingerprints wherein said electronic memory is configured to store the fingerprints of the current user that do not match the fingerprints of the previously authorized user.

2. The assembly according to claim 1, further comprising a power supply being coupled to said firearm, said power supply being electrically coupled to said processor, said power supply comprising at least one battery.

3. The assembly according to claim 1, wherein: said locking unit comprises a lock being coupled to said firearm, said lock being biased into a locking position having said lock mechanically engaging said action wherein said lock is configured to inhibit said action from being manipulated, said lock being electrically coupled to said processor, said lock being actuated into an unlocked position when said processor generates said unlock sequence having said lock mechanically disengaging said action wherein said lock is configured to facilitate said action to be manipulated.

4. The assembly according to claim 3, further comprising a button being coupled to said lock wherein said button is configured to be manipulated, said button urging said lock into said locking position when said processor generates said unlock sequence wherein said lock is configured to inhibit said action from being manipulated.

5. A biometric firearms safety system comprising:
a firearm having a grip and an action;
a fingerprint unit being coupled to said firearm, said fingerprint unit being positioned on said grip wherein said fingerprint unit is configured to read fingerprints from a current user, said fingerprint unit comprising:
a processor being coupled to said firearm,
an electronic memory being coupled to said firearm, said electronic memory being electrically coupled to said processor, said electronic memory storing fingerprints of a previously authorized user,
a plurality of sensors, each of said sensors being coupled to said grip wherein each of said sensors is configured to read the fingerprint from a respective finger of the current user when the current user grips said grip, each of said sensors being electrically coupled to said processor, said processor generating an unlock sequence when said sensors read fingerprints of the current user match the fingerprints of the previously authorized user stored in said electronic memory, said processor generating a record sequence when said sensors read fingerprints that do not match the authorized user's fingerprints wherein said electronic memory is configured to store the fingerprints of the current user that do not match the fingerprints of the previously authorized user, and
a power supply being coupled to said firearm, said power supply being electrically coupled to said processor, said power supply comprising at least one battery; and

a locking unit being coupled to said firearm, said locking unit engaging said action such that said locking unit inhibits said action from being manipulated wherein said locking unit is configured to inhibit said firearm from being fired, said locking unit being electrically coupled to said fingerprint unit, said locking unit disengaging from said action to allow firing said firearm, said locking unit comprising:
a lock being coupled to said firearm, said lock being biased into a locking position having said lock

biased into a locking position having said lock
